DOOR CHECK

Karl Kolbus, Milwaukee, Wis.

Application February 11, 1946, Serial No. 646,822

2 Claims. (Cl. 16—70)

1

My invention refers to spring controlled door checks and it has for its primary object to provide a compact convolute spring and link connection to a piston rod, mounted in a cylinder, whereby a door, in approximately full open position, neutralizes the spring pressure, which pressure gradually increases when the door swings to a closed position, to thus insure full spring tension to hold the door positively shut and relieve said pressure when fully opened.

A further object of my invention is to provide all door check actuating mechanisms within confines of the width of a door jamb, whereby clearance is had to attach an outside screen door when desired.

With the above and other objects in view, which will appear as the description proceeds, the invention resides in the novel construction, combination and arrangement of parts, substantially as hereinafter described, and more particularly defined by the appended claims, it being understood that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

In the drawings:

Fig. 1 represents a plan sectional view of a door mechanism having fitted thereto a spring controlled check embodying the features of my invention, with parts broken away and in section to illustrate structural features, the section being partly indicated by line 1—1 of Fig. 3.

Fig. 2 is a similar sectional view illustrating the door check mechanism in its full open position.

Fig. 3 is a fragmentary longitudinal sectional view of the same, the section being indicated by line 3—3 of Fig. 1.

Fig. 4 is a cross section through a bracket portion illustrating the pivotal connection between the same and a piston rod.

Fig. 5 is a cross section through the piston rod, the section being indicated by line 5—5 of Fig. 1; and

Fig. 6 is a cross section, as indicated by line 6—6 of Fig. 1.

Referring by characters to the drawings, A indicates a door frame having hinged thereto a door B. Secured to the strips of the door frame is a bracket 1 having extended therefrom a stud

2

2, journaled upon which stud is a lever 3 having a hub 3' retained thereon by a cotter pin.

The inner looped end of a convolute spring 4 engages the hub 3' and the outer coil of said spring is extended tangentially and secured to the base of the bracket by means of a stud 1' interlocked with a slot in the spring end.

At a predetermined distance from the door hinge, a flanged clip 5 is secured thereto. A cylinder head 6 is secured to the clip by a pivot bolt 5', which bolt extends through companion ears of said clip and cylinder head.

A cylinder 7 is secured to the head 6 and the inner end of said cylinder has secured thereto a second head 6', which second head is provided with free vent apertures, as shown in Figure 5 of the drawings and also a central slot 8 for sliding engagement with a flat piston rod 9, the slot in said head serving as a guide for the same.

The outer end of the piston rod 9 has secured thereto a piston 9' reciprocated within the cylinder. The inner exposed end of the piston rod is formed with an extended elbow 9'', which elbow is secured to the bracket 1 by a pivot bolt 10, the same being approximately at a right angle to the piston rod body 9.

The piston rod 9 at its junction with the elbow section 9'' has pivoted thereto a link 11 the opposite end of which link is pivoted to the end of the lever 3. In the back and forth swing of the door the lever 3 rotates upon its axis stud 2 through an arc of a circle approximating 50 degrees, whereby the coil spring under constant tension is partly wound and unwound.

In the position of the parts assumed in Fig. 1, the spring is exerting approximately a maximum tension upon the closed door.

When the door is swung to its open position, as illustrated in Fig. 2, the piston freely moves downwardly within the cylinder, while at the same time it swings upon its pivot connection to exert a slight winding tension upon the spring as the link 11 exerts an oscillating movement upon said lever, whereby, due to the angular position with relation to the link and pivot point of the piston elbow, the closing strain of the spring is neutralized, whereby the door may remain open, due to the fact that its load is sufficient to resist closing.

From the foregoing description it will be apparent, due to the toggle link connections between the spring and piston rod, the door is firmly closed, and when fully opened, it may rest in this open position. However, the door closure control may be regulated due to the fact that an air cush-

ion is developed between the piston 9' and head 6. The regulation of this cushion is obtained by a release vent 12 in the head 6, and said vent may be entirely cut off or varied by an adjustable tapered screw 12' in threaded engagement with the release vent.

I claim:

1. A door check comprising an angular bracket adapted to be secured to a door frame, a stud extending therefrom, a hubbed lever journaled upon the stud, a convolute spring having its inner end secured to the lever hub and its outer end secured to the bracket, a cylinder, a second head mounted upon the inner end of the cylinder, an air vent in said second head, a clip adapted to be secured to a door in pivotal connection with an outer head, a piston rod slidably guided in the second head carrying a piston mounted in the cylinder, the exposed end of the piston rod being provided with an elbow extension in pivotal union with the bracket and a link in pivotal union with the piston rod elbow and spring controlled lever.

5 2. A door check comprising a stud carrying bracket, a lever having a hub mounted upon the stud, a convolute spring connected to the lever hub and bracket, a headed cylinder adapted to be pivotally secured to a door, a piston therein, a piston rod carried by said piston, the piston rod terminating with an elbow approximately at a right angle to the main portion of the piston rod, a pivot connection between the piston rod 10 elbow and bracket, a toggle link connecting the spring controlled lever and piston rod elbow, and adjustable means for venting one end of the cylinder.
